UNITED STATES PATENT OFFICE

WILBUR S. LEWIS, OF CLEVELAND, OHIO, ASSIGNOR TO THE NESTLE-LE MUR COMPANY, OF CLEVELAND, OHIO, A CORPORATION OF OHIO

PERMANENT-WAVING HAIR CURLER

Application filed May 14, 1926. Serial No. 109,077.

My invention relates to hair curlers upon which strands of hair are carried while permanent waving operations are performed.

One of the objects of my invention is to provide an improved hair curler with an outer tubular section rotatable relative to the inner section to which the hair strand is anchored, but wherein the sections will retain a given relative rotative position.

10 Another object of my invention resides in the provision of a curler comprising relatively rotatable sections which may be readily associated and disassociated.

Another object of my invention is to provide an improved two part curler comprising a hair strand anchoring part and a hair winding part, which may be of different metallic materials, wherein these parts may be readily separated after use for cleaning purposes.

20 Other objects of my invention and the invention itself will be apparent by reference to the accompanying drawings wherein:

Fig. 1 shows a side elevation of an assembled curler comprising concentric tubular and rod parts, embodying my invention;

Fig. 2 shows a longitudinal sectional view through the tube, showing the rod in elevation.

Fig. 3 shows a side elevation of the tube detached from the rod; and

Fig. 4 shows a side elevation of the rod with the tube removed therefrom.

Referring to all the figures of the drawings wherein like reference characters designate like parts throughout the specification, at 1, I show a hair curler winding tube upon which the hair may be wound and stretched, and I show a rod 2 shown as generally cylindrical in form, and of slightly less diameter than the interior wall of the tube and of such greater length than the tube section as to project from the ends thereof.

A plurality of these hair curlers are simultaneously employed with a permanent hair waving machine during the "waving" operation performed therewith. Since the strands of hair partially support the curlers, the material from which the curlers are made is important and necessarily should be as light in weight as possible in order to reduce the

strain on the strands of hair and therefore the discomfort to the individual whose hair is being "waved" to a minimum. The rod is therefore usually made of light material such as aluminum.

I find that, during the waving operation, electrolytic action takes place between the tube and rod which are usually of different metals, the solution employed on the hair during the permanent waving process acting as an electrolyte; a borax solution commonly so used often causes this action. Relative rotation of the sections of the curler, after such electrolytic action, therefore becomes exceedingly difficult often necessitating the employment of tools in the effort. The use of tools is very undesirable, causing denting, and other injuries to the curler sections to such an extent that they must often be replaced with new curlers.

In my improved curler rod, I provide a rod, 2, one end of which is provided with a longitudinally extending slot 3 to which the strand of hair is tied, the other end of the rod preferably being flattened to provide a finger grip 4. An annular groove 5 is formed in the rod adjacent a shoulder 6 at the grip end of the rod. The rod has a longitudinal slit 9 extending through its middle in its intermediate portion, the portions 7 and 8 thus formed being spread outwardly, when the rod is free. These portions are spaced apart to a degree sufficient to cause the outer surfaces thereof to bulge beyond the other rod surface portions and thus provide resilient clutch surfaces 10 and 11 which bear frictionally against the inner wall of the tube, being compressed thereby when the tube and rod are assembled. The tension of the clutch relative to the tube can be regulated by the degree to which the spaced portions are preliminarily bowed. The tube is crimped inwardly near one end to make an annularly depressed portion adapted to enter the rod groove 5. The tube is longitudinally slit at its crimped end portion on each side at 13 and 15 to permit resilient spreading of the thus divided portions of the tube end.

The rod is telescoped into the tube until the annular shoulder 12 snaps into the annular

100

groove 5. The annular shoulder serves to retain the sections from relative longitudinal movement. The clutch is so compressed and carried to frictionally engage the inner wall 5 of the tube section as to create sufficient tension to overcome any unwinding tendency of the hair when stretched which would otherwise effect relative rotation of the parts.

Ready separation of the tube and rod may 10 now be effected, since the longitudinally slit tube forms spring arms 16 and 17 which press the annularly depressed grooved parts 12 into the groove 5, of the rod 2, and resiliently retain the same therein. When desired the 15 tube may be removed from the rod by gripping the tube in one hand and placing that end of the rod which is remote from the gripped end against a support and exerting slight manual force towards the support. 20 The two parts will separate by virtue of the resilient spreading of the parts 16 and 17 of the tube.

A two piece curler of simple construction can be assembled at a very low cost which can 25 be manually rotated in either direction to stretch the wound hair without relative longitudinal displacement.

In utilizing the curler for waving processes, a strand of hair is gathered from the head, 30 after being treated with a softening solution, and is tied adjacent the scalp by a string which is wedged into the slot 3. The strand of hair is then wound either over or under the end of the tube toward the end nearest 35 the finger grip and tied at the end by a string to the tube. The hair is secured to the rod and to the tube so that when the tube is held stationary the hair can be stretched lengthwise by rotating the rod in the same 40 direction as that in which the strand is wound upon the tube. When the hair has been sufficiently stretched to change its cross section the clutch will exert sufficient pressure against 45 the tube so that the curler parts will remain relatively stationary.

Having thus described my invention in a single embodiment, I am aware that numerous and extensive changes may be made in the same but without departing from the spirit 50 and scope of the invention, and I do not wish to limit myself to the embodiment herein illustrated and described.

What I claim is:

1. A curler comprising a tube element upon 55 which a strand of hair may be wound and tied, a rod element to which the strand is tied, said elements being manually rotatable relatively each to the other, means intermediate the ends of the tube to frictionally resist 60 relative rotation of the elements, and yielding means to restrain relative longitudinal movement of the elements.

2. A curler comprising a tube part upon 65 which a strand of hair may be wound and tied, a rod part to which the strand is tied,

said rod and tube being manually rotatable relatively each to the other, means intermediate the ends of the rod to frictionally resist relative rotation of the said parts, the rod having an annular groove adjacent one of its 70 ends, said tube being longitudinally slotted at one end and having an inward projection extending from its slotted portion adapted to be resiliently pressed within the annular groove of the rods to enable the parts to be 75 readily separated.

3. A curler comprising a tube element upon which a strand of hair may be wound and tied, a rod element to which the strand is tied, one of said elements having a bifurcated 80 spring end, the other element being annularly grooved, the groove adapted to receive a projecting portion of the fork of the other element, the elements being normally resiliently retained in relative telescoped position by 85 virtue of the resiliency of the fork of the bifurcated element, the parts adapted to be separated by exerting sufficient force upon them in opposite directions to overcome the resiliency of said fork.

4. A device of the class described comprising a tube having one end turned inwardly, and having an annular, inwardly extending rib near the other end, and a rod of smaller diameter than the bore of the tube extending through the tube in close engagement with the said inturned end and having an annular groove to engage with the said inwardly extending rib, the said rod being split lengthwise intermediate its ends and distorted to 100 have a spring-like, frictional engagement with the inner surface of the tube.

5. A curler comprising a tube, a rod extending therethrough and rotatable therein, and a resilient connection between the tube and 105 the rod preventing longitudinal movement of these parts relative to each other.

In testimony whereof I hereunto affix my signature this 10th day of May, 1926.
